UNITED STATES PATENT OFFICE

ADOLPH SCHULZ, OF MILWAUKEE, WISCONSIN

SAFETY BOOTH

Application filed February 14, 1930. Serial No. 428,486.

This invention relates to improvements in safety booths and more particularly to the type of cashier booth used in banks, and the like, where it is necessary to provide protection for the cashier in handling large sums of money.

One of the objects of my invention is the provision of an improved structure of the above type which is particularly adapted for cashiers' booths, although this type of booth can be used for other bank officials, especially those who are in the habit of handling large sums of money so as to prevent attempted burglarizing, and wherein the cashier or other official is not in direct line with the person with whom they are transacting business, and thus reducing to a minimum the danger to the cashier or other official during holdups.

20 As a general rule, attempts at holding up banks and similar places where large sums of money are accessible, cashier booths and the like are so constructed that the cashier usually faces the person with whom they are transacting business, thus a burglar can easily attempt to obtain, by armed force from the cashier, the contents of the booth and, it is, therefore, another object of my invention to provide a cashier's booth or similar structure wherein the cashier or other official is not in direct line with the party with whom they are doing business, making it practically impossible to force the occupant of the booth to give up the contents thereof.

35 A further object of my invention is the provision of a structure of the above character wherein the party desiring to transact business with the occupant of the booth must necessarily do so through the medium of reflecting mirrors which are so positioned that the occupants of the booth can readily see with whom they are transacting business, and the party desiring to transact business can readily see the cashier through these reflecting mirrors, and suitable means is provided for conveying money, checks, or similar articles between the two parties, thus the business can be transacted with the cashier or other official in the background, but not in

direct line with the party with whom they are transacting the business.

A still further object of the invention is the provision of an improved means whereby the cashier or other official may entirely shut off any communication from the party with whom they are doing business, so that there is no possible chance of forcing the cashier or other official to give up the contents of the booth, thus reducing to a minimum the chances of burglarizing a bank or similar institution by armed force.

With the above and other objects in view, the invention consists in the novel features of construction, the combination and arrangements of parts hereinafter more fully set forth, pointed out in the claim and shown in the accompanying drawings wherein:

Figure 1 is a detail vertical sectional view through the desk portion of a cashier's booth, constructed in accordance with my invention, showing the means of communication between the cashier or other official and the party with whom they are transacting business;

Figure 2 is a full section of a booth taken at right angles to the showing in Figure 1 and illustrating the movable door for entirely cutting off communication between the cashier and the other party;

Figure 3 is a view taken at right angles to Figure 2, showing the relative arrangement of the booth;

Figure 4 is a horizontal sectional view of the form shown in Figure 3;

Figure 5 is a vertical sectional view of a modified form of booth;

Figure 6 is a sectional view similar to Figure 5, showing another form of the invention; and,

Figure 7 is a horizontal section showing still another form of the invention.

There are several ways in which a cashier's booth may be constructed in accordance with my invention, particularly with regard to the arrangement of the mirrors whereby the cashier may readily view the party with whom they are transacting business and the party with whom they are transacting business may readily view the cashier, although

there is a solid protecting wall between the two parties.

However, the main structure will include an enclosure 1, and this enclosure has two entrances thereto, one for the cashier and one for the parties who desire to transact business with the cashier. The cashier's side may be connected up directly with a main hallway 2 and with a branch hallway 3, having a communicating door 4 which may lead to any other part of the building.

Within the enclosure 1, I provide a desk-like part 5, which extends transversely the entire width of the enclosure and midway between the side walls of the enclosure, I provide a partition 8 which projects into the desk-like portion 5 a suitable distance, as shown in Figure 4, so as to provide substantially two separate compartments within the enclosure.

This partition wall 8 extends into the desk-like member 5, slightly beyond the longitudinal center of the same and at one side of the partition I provide a grating 9 which is preferably in that side of the enclosure where the party desiring to transact business with the cashier enters and across each corner of the inside portion of the enclosure and above the desk-like member 5, I provide two mirrors 10 and 10' which are disposed at an angle, as shown in Figure 4, so that the party in front of the grating 9 can readily look into the mirror 10 and through reflectors will observe the cashier in the mirror 10' and the cashier will, by looking in the mirror 10', observe the party with whom they are transacting business through the reflection in the mirror 10.

From the above, it will be apparent that a party desiring to transact business with the cashier or other official in the enclosure 1, will enter one side of the enclosure through the door 11 and may communicate with the cashier through any suitable means for conveying the voice, and in the present instance, I have illustrated a connecting tube 12 which communicates between the two sections of the enclosure and is provided with mouth pieces 13 on the ends thereof, as illustrated in Figure 1. It will be apparent that other means may be used for the purpose of conversation between the two parties in the enclosure, although by speaking comparatively loud, the two parties within the enclosure 1 can talk back and forth in view of the fact that in front of the partition wall 8, the space between the two sections of the enclosure is opened.

In order that checks, money, or other valuable papers may be conveyed from one section of the enclosure to the other I provide a movable drawer 14, slidably mounted within a guideway 15 and provided with a downwardly projecting slotted arm 16, a pin 17 being movable within the slot in the arm 16

and carried by a fulcrumed lever 18. The lower end of lever 18 carries a pinion 19, meshing with the pivotally mounted rack 20. The rack 20 is normally retained in one position, as shown in Figure 1, by means of a coil spring 21. The pivot rod 22 upon which the rack 20 is mounted extends laterally and is provided at one end with a hand lever 23, preferably located within the cashier's section of the enclosure so that the cashier or other official can easily manipulate the operating mechanism for moving the drawer 14 from one side of the partition 8 to the other.

It will be apparent from the foregoing that a party entering one side of the enclosure 1 and having a desire to cash a check, can place the check in the drawer 14 and the cashier will then pull the drawer toward his side of the enclosure, removing the check and place the correct amount of currency in the drawer, and then move the drawer back to the other side of the partition, so that the party can remove the currency desired. Other valuable papers can be transferred to the cashier in a similar manner.

Attention is directed to the fact that while the space between the inner edge of the partition 8 and one wall of the enclosure 1 is opened, this can be quickly and readily closed by the cashier or other occupant of the inside of the enclosure, should it be found necessary.

The structure illustrated, discloses a sliding door 24 which is mounted within the partition 8 and actuated by means of operating mechanism controlled from the inside by the occupant of the enclosure. The operating mechanism for the door 24 includes a link 25 pivotally mounted to the inner edge of the door, as shown in Figure 2. This link is loosely connected to a pivotally mounted lever 26, the upper end of the lever carrying a rack 27 which meshes with a pinion 28 so that when the pinion 28 is rotated in any desired manner, the rack 27 will be actuated, rocking lever 26 upon its pivot and force the door 24 forwardly from the partition 8 so as to close the space between the two sections of the enclosure.

It will be noted that by providing the sliding door 24 within the partition 8, communication may be cut off between the two sections of the booth, so as to prevent the possibility of injury to the cashier or other official, through the means of a gas bomb or through the use of poisonous or other injurious fluids.

In Figure 5, I have illustrated another form of the invention wherein the enclosure 1 is divided into upper and lower sections *a* and *b*. A desk 29 and 29' is placed in each section *a* and *b* respectively. The two sections *a* and *b* are arranged one above the other, and positioned vertically at the open side of each section in a single mirror 30, whereby the parties within the two sections can read-

ily observe each other as the business is being transacted. Similar means of communication between the two sections of the booth shown in Figure 5 can be used as disclosed in the preferred form of the invention.

In Figure 6 I have illustrated the same relative construction as shown in Figure 5, with the exception of having two mirrors 31 and 31' disposed at such an angle that the reflections from the two sections of the booth will be such that the parties within both the upper and lower sections of the booth can readily observe each other during the transaction of any business.

In Figure 7, I have illustrated another form of the invention wherein the enclosure 1b has the partition 8' extending from one corner to a point beyond the center of the booth and in the opposite corner, the desk 20 part 5' is located with a single mirror 32, positioned transversely across one corner of the booth so that the parties on each side of the partition 8' can readily view each other during the transacting of any business.

Each section of the booth 1b is also provided with an entrance door 33, whereby they can readily gain entrance to either section of the booth. It will be apparent from the foregoing description taken in connection with the accompanying drawings, that I have provided an improved structure of the character set forth above, wherein a cashier or other official is suitably housed so that it is practically impossible to complete a holdup due to the fact that the cashier or other official is in no danger of being injured or killed outright by a holdup person, as the partition wall not only protects them, but the cashier can readily observe all of the movements of the other party and can quickly give an alarm of an attempted holdup without placing themselves in any danger from the holdup party.

This improved structure is comparatively simple and can be installed in banks, or similar institutions, at a very low cost, and due to the fact that it assures the safety of the cashier or other official against danger by a holdup person, it will insure confidence in the occupant of the booth so that they will readily retain the presence of mind and sound the alarm and at the same time, if necessary, can actuate the mechanism for closing the door 24, thus insuring positive safety from a holdup.

While I have shown and described the preferred embodiment of my invention, it will be apparent that slight changes may be made in the construction when putting the invention into practice without departing from the spirit of the same or the scope of the appended claim.

I claim:

A device of the class described including a booth, a desk portion at one side of the booth,

a partition arranged centrally of the booth between one wall and the desk portion, a sliding door movable in the partition and adapted to close the open space between the partition and the opposite wall with the door operating above the desk, angular mirrors disposed in opposite corners of the booth above the desk, and means forming communication between the chambers formed by the partition.

In testimony that I claim the foregoing I have hereunto set my hand at Milwaukee, in the county of Milwaukee and State of Wisconsin.
